Detailed Important Risk Information For ADVATE

CONTRAINdications

Some patients receiving ADVATE to the product may be at risk for anaphylaxis, (recurrent), anaphylactic reactions, and/or anaphylactic shock. If anaphylaxis occurs, it is important to give resuscitation, including epinephrine, and/or hospitalize the patient.

WARNINGS & PRECAUTIONS

Hypersensitivity reactions are possible with any product. Advate may have these side effects. Reactions, including anaphylaxis, have been reported with other monoclonal immunotherapy
